MERCURY BOILER DRUM

Howard J. Kerr, Westfield, John Prentice, Bayonne, and George D. Ebbets, Kenilworth, N. J., assignors to The Babcock & Wilcox Company, Bayonne, N. J., a corporation of New Jersey

Application November 16, 1928, Serial No. 319,978

10 Claims. (Cl. 122—312)

This invention relates to a cylindrical drum mercury boiler that is provided with a displacer of such form and location as to decrease the amount of mercury that would otherwise be required and to insure good circulation of vapor and liquid to keep the tubes from burning. The invention will be understood from the description in connection with the accompanying drawings, in which Fig. 1 is a vertical section through a furnace above which the boiler is installed; Fig. 2 is a vertical section through the drum showing an illustrative embodiment of the invention; and Figs. 3 and 4 are similar sections showing modifications.

In the drawings reference character 1 indicates a furnace that may be fired in any convenient way. The horizontally disposed cylindrical mercury boiler drum or casing 2 is located above an extension at the rear of the furnace so that the hot products of combustion from the furnace heat the tubes 3 depending from the drum 2 during their passage upward, after which they pass around the drum 2 or between several of such drums into the stack. The drum 2 may be supported by tension members 4 that are hung from supports 5 that may be in the form of transverse I-beams and these tension members are preferably located out of the path of the hot gases. As shown they are protected by the end walls of the furnace extended upward.

The drum 2 is provided with a combined displacer and baffle, preferably in the form of a solid block of metal 6 having a curved bottom 7 corresponding approximately to the shape of the inner surface of the drum 2 and being spaced therefrom to provide a space 8 between the displacer 6 and the drum 2 that preferably gradually increases in size upwardly. The upper surface of the displacer 6 is made flat, as indicated at 9, and is level. A flange 10 extends around the edges of the flat top 9, and partitions 10' having holes therein extend across the same and support a feed pipe. The flat level top of the displacer is below the normal liquid level and the flange 10 forms a pool from which liquid cannot flow except to the tubes.

Holes or tubes 11 are provided through the displacer 6 from the level flat top surface 9 thereof. Tube displacers or cores 12 are located in the tubes 3 so as to provide narrow annular spaces next to the tubes and small central holes 13 are provided extending longitudinally through the displacers 12 ending near the closed bottom ends of the tubes. The tubes are preferably made straight and may be made of unequal length to

provide a slag screen effect especially when powdered coal is used for the fuel. Nipples, sleeves or ferrules 14 that are proportionately long are connected at their top ends to the holes 11 near the surface 9 of the drum displacer 6 and at their lower ends to the upper ends of the holes 13 in the tube displacers 12. These nipples 14 are slightly smaller than the holes 11 and being long, a certain amount of flexibility is provided in them to permit relative movement of the parts. They are preferably made of equal lengths.

The lower portion of the drum 2 is thickened as shown at 15, and holes 16 are provided, into which the tubes 3 may be welded or otherwise secured so as to remain tight.

Curved separator baffles 17 are provided in the upper part of the drum over the displacer 6 and extend inwardly from the walls of the drum 2. These separator baffles 17 are so located as to receive mixed liquid and vapor rising between drum and displacer, changing its direction so that the liquid mercury will be separated from the mercury vapor and will collect as a pool on the flat level surface 9 of the displacer 6 and be prevented from flowing off of the edges thereof by means of the lip or flange 10. A feed inlet 18 is provided for feeding mercury into the drum 2 to the pool on the surface 9, and may rest upon the edges of the cross partitions 10'.

The drum displacer 6 which is shown as a solid block may be hollow without departing from the invention and the same is true of the tube displacers 12.

The operation is as follows: The heat from the furnace 1 causes the mercury in the thin annular space next to the tubes 3 to be vaporized. The mercury vapor and entrained mercury pass upwardly with considerable velocity through the annular spaces between the tube displacers 12 and the tubes 3 and then enter the narrow space 8 between the drum displacer 6 and the drum 2 and follow along the inside walls of the drum to the separator baffles 17. The separator baffles cause the liquid mercury to be separated from the vapors and pass into the pool of mercury confined by the lip 10 on the level top of the drum displacer 6. The liquid mercury then passes downwardly through the flexible nipples 14 in drum displacer 6 into the holes 13 in the displacers 12 and then into the closed bottom ends of the tubes 3, and thence into the narrow annular spaces between the displacers 12 and the tubes 3 where some of the mercury is vaporized.

The mercury vapors are taken off from the drum 2 through one or more outlet pipes for mer-

cury vapor (not shown) provided at the upper side of the drum 2 in the usual manner.

In the modification shown in Fig. 3 the drum displacer 20 has a lower surface which conforms somewhat to the shape of the drum 2, and has its edges extended upwardly to form a pool space 21 for the collection of mercury. The drum displacer 20 is spaced from the drum 2 by means of spacers 22. The flat pool space along the level upper side of the drum displacer 20 for the collection of mercury is partially filled with another displacer 23 that is spaced from the displacer 20 and its lips by the spacers 23'. A frame work 24 extending from the top of the inside wall of the drum 2 is provided with adjustable bolts 25 which serve to keep the displacer 23 immersed in the mercury against its tendency to float. This in turn holds down displacer 20. The curved separator baffles 26 are similar to the separator baffles 17, shown in Fig. 2, and are used for a similar purpose. In this modification of the invention the tube displacers or cores 28 in the tubes 3 are hollow and are made up of two tubes one within the other having their ends connected. To provide enough length to make the nipples or sleeves 30 flexible in this uniformly thick drum, the lower ends are fastened to the tube displacers some distance below the top of the displacer. Plates 32 may be provided partly across the upper ends of the tubes 3 to hold the displacers 28 in position. The mixture of mercury and mercury vapor will impinge against these plates and cause the two to be separated to a certain extent. The operation is similar to that already described.

In the modification shown in Fig. 4, the elements are much like those shown in Fig. 3, except that the liquid surface displacer 23" in the space above the level upper side of the block 20 is sufficiently thick to bring its upper surface above the level of the pool of mercury in the displacer 20 and to confine the free surface of the liquid to the narrow space next to the lip of the drum displacer 20.

By providing a second drum displacer 23' or 23" a smaller amount of mercury can be used and still insure a proper flow of the liquid mercury to each of the tubes 3.

The drum displacer not only minimizes the mercury volume required but serves itself as a guide to the circulation in the drum and it is wholly submerged in the liquid except for the edge lips. When an auxiliary drum displacer is used as in Fig. 3 and Fig. 4 to displace some of the liquid in the pool in the main displacer, it may be submerged as in Fig. 3 or be made high enough to extend above the liquid level as in Fig. 4. In either case it is understood that the auxiliary drum displacer is in effect a part of the main drum displacer and may be constructed to be an integral part though it is shown as a separate piece for convenience in construction and assembly. The drum displacer is itself the drum circulation guide and with its lips above the liquid level it prevents any reversal of circulation as well as any interference of rising with falling legs of the circuit.

We claim:

1. In a mercury boiler, a cylindrical drum; a displacer in the lower portion of said drum spaced therefrom, said displacer being so shaped that the space gradually increases in size upwardly, tubes depending from said drum, and connections through said displacer to said tubes.

2. In a mercury boiler, a cylindrical drum, a displacer in the lower portion of said drum spaced

therefrom having its lower surface conforming substantially to the inner surface of said drum, and tubes depending from said drum, flexible connections extending to said tubes from near the upper surface of said displacer.

3. In a mercury boiler, a cylindrical drum, a displacer in the lower portion of said drum spaced therefrom having a lip around its upper surface, said displacer except its lip being below the normal mercury level, tubes connected to said drum and connections through said displacer to said tubes, said connections comprising flexible nipples.

4. In a mercury boiler, a cylindrical drum, a displacer in the lower portion of said drum spaced therefrom having a lip around its upper surface, said displacer except its lip being below the normal mercury level, tubes connected to said drum and connections through said displacer to said tubes, said connections comprising flexible nipples of substantially equal lengths.

5. In a boiler structure, the combination of a casing, boiler tubes connected to the casing, said boiler tubes being provided with tubular cores, a baffle plate in the casing provided with passages for the flow of liquid, said passages being at least equal in diameter to the core passages, sleeves mounted in the baffle plate passages and projecting into the core passages in spaced relation to the walls thereof for conveying liquid from above the baffle plate to the core passages, and means forming a seal for preventing flow of vapor around said sleeves into the tubular core passages.

6. In a boiler structure, the combination of a casing, boiler tubes connected to the casing, a baffle plate in the casing provided with passages for the flow of liquid to the boiler tubes, and sleeves connecting said passages to the boiler tubes, said sleeves having flanges which engage the walls of the adjacent passages over a limited area in an axial direction.

7. In a boiler structure, the combination of a casing, boiler tubes connected to the casing, said boiler tubes being provided with tubular cores, a baffle plate in the casing provided with passages for the flow of liquid, said passages being at least equal in diameter to the core passages, and sleeves mounted in the baffle plate passages and projecting into the core passages and in spaced relation to the walls of at least one of said passages and for conveying liquid from above the baffle plate to the core passages, the ends of said sleeves forming a fluid tight joint with the walls of the respective passages.

8. In a boiler structure, the combination of a casing, boiler tubes connected to the casing, said boiler tubes being provided with tubular cores, a baffle plate in and spaced from the walls of said casing to form vapor flow spaces therebetween provided with passages therethrough for the flow of liquid, said passages being at least equal in diameter to the core passages, and sleeves mounted in the baffle plate passages and projecting into the core passages and arranged to provide a yieldable connection therebetween.

9. In a mercury boiler, a casing, a baffle within and spaced from the walls forming the lower portion of the casing to form vapor flow spaces therebetween and concave on its upper surface to receive and guide liquid, said baffle having passages therethrough, boiler tubes connected to said casing and each provided with a tubular core spaced from the walls of its respective tube, and a sleeve for each baffle and core passage and in fluid tight relation thereto.

10. In a mercury boiler, a casing, a baffle within the lower portion of the casing and concave on its upper surface to receive and guide liquid, said baffle having passages therethrough, boiler tubes connected to said casing and each provided with a tubular core spaced from the walls of its respective tube, a sleeve for each baffle and core pas-

sage and in fluid tight relation thereto, and a displacer within the concavity of the upper surface of the said baffle.
